UNITED STATES PATENT OFFICE.

THEODORE W. FRENCH, JR., OF CLEVELAND, OHIO.

LAMP-BASE.

No. 875,796.

Specification of Letters Patent.

Patented Jan. 7, 1908.

Application filed March 27, 1907. Serial No. 364,756.

To all whom it may concern:

Be it known that I, THEODORE W. FRENCH, Jr., a citizen of the United States, residing at Cleveland, in the county of Cuyahoga and 5 State of Ohio, have invented a certain new and useful Improvement in Lamp-Bases, of which the following is a full, clear, and exact description.

The object of the present invention is to 10 provide an improved form of base for incandescent lamps.

The particular purpose of the invention is to produce a base which shall not only conform to the conditions imposed by the necessities of utility and manufacture and the requirements of the fire underwriters and yet be a marked advance in the art both as to simplicity and cheapness of construction.

The base which I have produced has these 20 advantages and certain additional and valuable characteristics in the matter of weight and freedom from breakage.

Referring to the accompanying drawings which illustrate an embodiment of my invention, Figure 1 is an elevation of a base constructed according to my invention. Fig. 2 is an enlarged detail section showing the features of construction.

In the manufacture of bases for electric 30 lamps it has been found necessary to have a portion of the base provided with a standard screw thread so that all bases may be applied to all sockets. This is a commercial requirement that is practically imperative. It 35 is, however, not possible to have the necks of the lamp-bulbs the same size, owing to the variety of styles of filament inserted therethrough, so that it has not been found a feasible thing to insert the necks of the bulbs in 40 the screw threaded portion of the base or to make the neck holding portion of the base of the same diameter as the screw threaded portion which is fixed into the socket. These conditions developed that feature of construction in bases which amounts to an enlarged skirt which, when the base is screwed 45 into the socket, projects out beyond the latter so as to be exposed. The fire underwriters have regarded this as dangerous, so 50 that it has become common practice to make the skirt of a separate piece, either of insulating material, such as porcelain or plaster of paris, or else of metal which is insulated by an annulus of porcelain from the screw 55 threaded metallic sleeve which engages with the socket.

It has been found, in practice, that to have the skirt formed of porcelain is not altogether satisfactory since it is not only heavy but fails to respond with readiness to the 60 heat of the lamp thus causing the cracking of the neck of the bulb which has a higher rate of expansion. That form of base in which the skirt is made of metal and separated from the metallic screw thread by an insulating porcelain insert, is, owing to the number of parts, and time required in fitting, 65 rather expensive to make and the consequent liability to breakage and the cost of transportation in large quantities are features of much concern.

According to my invention, I have constructed the shell of the base of a continuous piece of metal, one portion of which, A, is shaped to a screw thread of the standard 75 size and is adapted to be fitted into the standard socket in the ordinary way. The other end, B, of the base, is enlarged and would project from the socket so as to receive the bulb. Obviously, this form of 80 base, being of thin metal and capable of being formed of one sheet at a single stamping, has advantages of manufacture not possessed by any other form and it is also much lighter than those forms in which the thick 85 and heavy porcelain insulators are employed, but a base of such simple construction would not meet the requirements of the fire underwriters. I have discovered, however, that the structure may be perfected by insulating 90 the skirt in the following manner not only without producing an unsightly object but, as a matter of fact, improving the finish simultaneously with effecting the insulation. I first apply a layer C of japan to the exterior portion which will be exposed and to the interior portion, also, a short distance within the edge. Before this layer of japan dries, I apply thereover a layer of fibrous insulating material D which should be pliable and 95 absorbent. This insulating material covers the exposed portion of the base and is turned in over the edge of the skirt for a short distance. I thereupon apply a second coating E of japan and bake it. The japan is itself 100 an insulator but would, if applied to the metal directly and unprotected, be readily chipped off, whereas, in my construction, the inner coating is protected by the fibrous layer while the outer coating is held by this 105 pliable material instead of by the metal and consequently will not crack or chip.

I have used paper and cloth for forming the layer of fibrous pliable insulator and find that each works well, it being merely necessary that this layer shall be an absorbent 5 of the japan and have that pliancy which makes it conform readily to the shape of the base, and form, in conjunction with the japan, an insulating material which does not chip or fall from the base.

10 It is unnecessary to dwell upon the advantages in handling and shipment of a base of this construction since these are obvious to all those skilled in the art, but attention is particularly directed to the simplicity of 15 construction and rapidity with which such bases may be made as distinguished from those in which the various parts of the shell are assembled of different materials.

Having thus described my invention, I 20 claim:

1. An incandescent lamp base having a projecting skirt, said skirt being coated with a closely adherent fibrous insulating material.

2. An incandescent lamp base having a 25 skirt, said skirt being coated with an adhesive substance and an outer layer of pliable fibrous insulating material.

3. A lamp base comprising a continuous metallic shell having a skirt, said skirt being coated with an adhesive insulating substance 30 and a layer of absorbent pliable fibrous material.

4. A lamp base having a skirt, said skirt coated with a layer of adhesive substance covered by a fibrous material having a coating 35 of insulation thereover.

5. A lamp base having a skirt, said skirt coated with an adhesive substance covered by a fibrous material having thereover a coating 40 of a shellac containing substance.

6. A lamp base comprising a continuous metallic shell shaped to have a skirt for receiving a lamp bulb, the skirt being insulated externally and about its edge by a coating of insulation having a fibrous body 45 with a coat of shellac containing substance thereover.

In testimony whereof, I hereunto affix my signature in the presence of two witnesses.

THEODORE W. FRECH, Jr.
